UNITED STATES PATENT OFFICE.

ROBERT S. CARTER, OF CHICAGO, ILLINOIS.

GARMENT-SUPPORTER.

1,074,605.

Specification of Letters Patent.

Patented Oct. 7, 1913.

Application filed September 14, 1912. Serial No. 720,335.

To all whom it may concern:

Be it known that I, ROBERT S. CARTER, citizen of the United States, and resident of Chicago, in the county of Cook and State 5 of Illinois, have invented certain new and useful Improvements in Garment-Supporters, of which the following is a full, clear, and exact specification.

This invention relates to improvements 10 in garment supporters in which the garment is clasped between the free end of a fixed jaw and a pivoted movable jaw, the movable jaw of which is locked in its operative position by means of a cam or eccentric formed therewith, and more particularly to garment supporters which are especially adapted 15 for use as hose supporters.

Prior to my invention there have been 20 several serious objections to hose supporters now upon the market, and among which objections may be mentioned the frequency with which they cut holes in the hose, even when the edge of the clamping jaws are not serrated but smooth, and for the reason 25 that the movable jaw swings from a fixed axis, and that it cannot adjust itself to the fixed jaw or unevenness in the hose at the point clamped, as for example, when one portion of the length of its edge presses 30 simultaneously against a comparatively unyielding seam and the yielding fabric of the hose so that there is a side pull, eventually wearing through or cutting a hole in the hose, and furthermore that when the movable 35 jaw clamps the hose as tight as it should be for safety of hold thereon, it can only be loosened and detached by taking hold of it with the fingers, which is not infrequently quite painful to the operator.

The object of my invention is a garment 40 supporter, the opposing edges of the fixed and movable jaw of which are both straight and smooth, and the movable jaw pivotally supported in such a manner that concurrently 45 with its pivotal swinging movement it shall also have an end thrust, whereby it may be moved to its operative position without directly pinching a hose between it and the edge of the fixed jaw.

A further object of my invention is to 50 have the movable jaw so suspended that it may be operated to and from its closed position by means of a lever and in such a manner that there can be no necessity for taking 55 hold of the movable jaw with the fingers to loosen it or detach it from the hose, which

lever also serves to lock the movable jaw against accidental detachment from its operative position.

A further object of this invention is a 60 garment supporter and particularly one adapted for supporting hose, of the simplest possible construction, and fewest number of parts, of durable construction, in which it is possible and practical to secure the objects 65 above mentioned.

With these ends in view, my invention finds embodiment in certain features of novelty in the construction, combination and arrangement of parts by which the said 70 objects and certain other objects are hereinafter attained, all as fully described with reference to the accompanying drawings, and more particularly pointed out in the claim. 75

In said drawing: Figure 1 illustrates in side elevation a garment supporter in its operative position, locking a garment and particularly hose thereto. Fig. 2 is a similar view showing the jaws open, and Fig. 3 80 is a front elevation thereof.

Similar characters of reference indicate the same parts in the several figures of the drawing.

The body portion of the fixed jaw of my 85 garment supporter preferably consists of a sheet metal plate 4, from one end of which is bent a hook-like portion forming the jaw 5 thereof, the edge 6 of which preferably extends the full width of the plate 4, the opposite edges 7-7 of the plate preferably converge and terminate in a slot 8, to which (see Fig. 1) a strap 9 may be secured for suspending the holder in its entirety from an upper garment of the wearer, as for example from corsets. 95

From the side edges of the plate adjacent the slotted end are outwardly bent lugs 10-10 forming bearings for lugs 11-11 projecting laterally from a lever 12, provided at its outer end with a thumb portion 13 for convenience of manipulation, as hereinafter described. Lever 12 is provided with a bent tongue 14 cut therefrom, forming a bearing for a movable jaw 15 provided 105 with a slot 16 (see Fig. 3) the width of which slot is somewhat greater than the thickness of the bent tongue, and also somewhat longer than the width of the tongue, so that the movable jaw may have a slight 110 endwise and also lateral movement on its bearing for adjusting its edge to any un-

evenness in the fabric held between the end of the movable jaw and in the pocket formed by the hook 5 on the fixed jaw, in order that the strain of an uneven fabric held between the two jaws may be uniformly distributed throughout the width of both jaws. Lever 12 has preferably formed therewith inwardly beyond its pivotal point, an angular bent portion 17, so formed with 5 a foot 18 that when the lever is in the position shown in Fig. 1 the lever will be locked, and also the movable jaw held against accidental outward movement. It will now be observed that the fabric 19 of a garment, as 10 for example the upper portion of a hose, is not clamped directly between the opposing straight edges of the jaws, but is bent over the edge of the fixed jaw and under the edge of the movable jaw, and that by having the 15 movable jaw self adjustable both laterally and longitudinally by means of the slot 16 working loose on its pivot, the strain or pull upon a hose or other garment will be uniformly distributed along the entire width of 20 both jaws, and that after inserting the fabric to its operative position in the fixed jaw, it is not compressed between the two jaws until the movable jaw has been swung inwardly past the edge of the fixed jaw. In 25 other words after inserting the fabric to its operative position relative to the fixed jaw with the movable jaw and the lever in their open position as shown in Fig. 2, it will now be seen that with the fixed jaw suspended 30 from the lever, as shown, and capable of lateral and longitudinal movement on its pivot as before described, it will move freely over the fabric lying across the edge of the fixed jaw as the lever 12 is moved toward its 35 locked position, preceding the locking of which, however, the movable jaw will then be thrust down toward the hook portion of the fixed jaw, for the reason that it will then have reached the limit of its longitudinal 40 movement and by the cam like action of the tongue be forced against and pinch the fabric against the curved inner wall of the hook, but being still free to move laterally, will also at the same time adjust itself to unevenness in the fabric in such a manner that 45 the strain upon the fabric will be uniformly distributed the full width of the compressing edge of the movable jaw. As a means for adjusting both jaws to unevenness in the 50 fabric such, for example, as occurs from seams partly clamped therein, this lateral 55

and longitudinal shifting of a movable jaw on its pivotal support is regarded as an important feature of my invention, and this whether the movable jaw is suspended by 60 and from a lever, or by other means of support.

When the lever is in its closed position, shown in Fig. 1, the foot 18 will lie flat against the plate 4 at a point thereon which 65 may be said to be the upper end of the shank of the fixed jaw, and thereby lock the lever against an accidental outward movement, and yet enable the lever to be quite easily started from its locked position. 70

It will now be observed with respect to the movable jaw and its suspending lever that their connection is a shifting fulcrum by means of which the movable jaw not only has a pivotal movement, but also a thrust 75 movement, providing for first a swinging movement inwardly beyond the edge of the fixed jaw without pinching the goods, and then a thrust movement clamping the goods against the curved portion of the fixed jaw 80 and not only enabling the movable jaw to adjust itself to unequal thickness and hard and soft places in the fabric, but in such a manner that the strain of the fabric is evenly distributed entirely across the ends 85 of both jaws. My invention is, therefore, not limited to the special devices and arrangement of devices herein described, but includes any shifting fulcrum support for the movable jaw accomplishing the results 90 next above recited.

Having described my invention, what I claim and desire to secure by Letters Patent is:

A garment supporter comprising in combination a fixed jaw, provided with lugs bent therefrom, a lever pivoted to said lugs, a loop bent from said lever, a movable jaw pivoted to said loop provided with a slot of greater length and width than the width 100 and thickness of the loop, whereby on operating the lever said jaw has a shifting fulcrum movement thereon, substantially as described.

In witness whereof, I have hereunto set 105 my hand and affixed my seal, this 11th day of September, A. D. 1912.

ROBERT S. CARTER. [L. s.]
